D. HAZZARD, OF MILTON, DELAWARE.

Letters Patent No. 72,037, dated December 10, 1867

IMPROVEMENT IN PLATFORM-SCALES.

The Schedule referred to in these Letters Patent and making part of the same.

TO ALL WHOM IT MAY CONCERN:

Be it known that I, D. HAZZARD, of Milton, in the county of Sussex, and State of Delaware, have invented new and improved Platform-Scales; and I do hereby declare that the following is a full, clear, and exact description thereof, which will enable those skilled in the art to make and use the same, reference being had to the accompanying drawings, forming part of this specification.

This invention relates to a new and improved method of constructing scales of the platform kind; and it consists in attaching a spiral spring to a spindle, to the top end of which spindle the platform is secured, and to the bottom end of which an indicating-rod and finger is attached, so that when an article to be weighed is placed on the platform, the weight of the article will act upon the spring, and be indicated by the finger, as will be hereinafter described.

Figure 1 represents a vertical section of the scale, through the line $z z$ of fig. 2.

Figure 2 is a horizontal section, through the line $y y$ of fig. 1.

Figure 3 is a view of the top of the stand.

Similar letters of reference indicate corresponding parts.

A is a hollow stand, which is secured to a bed-plate marked B; C is the spindle, D is the spiral spring, E is the platform. F represents a plate, which is secured to the stand to which the spring is attached, and through which the spindle C passes. The spindle is kept steady and in place by four friction-rolls $b b b b$, secured in the top of the stand, as seen in the drawing. G is an elastic rod, which is attached to the bottom end of the spindle, the lower end of which elastic rod is curved, and passes through the side of the stand, and forms a pointer or indicating-finger, h , on the plate H, a top view of which plate is seen in fig. 2. J is a tubular cavity within the stand A, which contains the spring, and K is a cavity of larger diameter, into which the spindle and lower end of the spring extend in the process of weighing. This latter tubular cavity is seen in section in fig. 2. The lower end of the spindle is attached to a plate, L, on which plate are secured, on pivots or arbors, friction-rolls $e e e e$, which serve to keep the spindle in a central position as it is depressed in weighing.

As the spring and rod are pressed down in the process of weighing, the elastic rod G, with the indicator h , will slide in the slot in the plate H, indicating thereby the weight of the article on the platform, the plate H being properly graduated and figured for the purpose, as seen in the drawing. The elastic rod G is guided or kept in place by bars $c c c$, which pass through the cavity K in the stand. The operation is so plainly shown in the drawing that further description is deemed unnecessary.

Having thus described my invention, I claim as new, and desire to secure by Letters Patent—

The hollow stand A, the spindle C, the springs D, the elastic rod G, and the graduated plate H, in combination, and arranged substantially as shown and described, for the purposes set forth.
